ALBUM

Albert A. Ainsworth, Ossining, N. Y.

Application April 6, 1936, Serial No. 72,876

6 Claims. (Cl. 129—20)

This invention relates to albums, folders, display cards, easels, and the like. The invention is disclosed herein as embodied in photograph albums, but it is applicable to other record or display devices, and particularly albums or cases for carrying photographs of machinery, furniture and the like by salesmen instead of displaying samples of the goods to be sold, and for the carrying of fabric samples such as woolens. For the purpose of disclosure the invention will be described primarily with reference to its use in a photograph album. It is to be understood, however, that as to those features applicable to single supporting sheets or easels, such structures are regarded as within the scope of the invention, and as to those features applicable to cards, slips or fabric samples, such structures are regarded as within the scope of the invention as set forth in the appended claims.

It is an object of the invention to provide means for hingedly mounting a multiplicity of photographs in stepped relation, together with means for retaining the photographs, fabric samples, etc., against the mounting sheet when the sheet is turned or held in any attitude likely to cause the photographs, fabric samples, etc., to fall away from the sheet. One important advantage of thus holding the photographs, fabric samples, etc., down except when they are to be individually examined lies in the fact that there is no danger of the photographs, fabric samples, etc., hanging downward and striking the opposite sheet when a sheet is turned over. Mutilation of the photographs, fabric samples, etc., and abuse of the hinges is thus avoided.

It is a further object of the invention to provide an album having a compartment for the storage of spools of small film or other articles.

It is a further object to provide an album, sample book or carrying case having a multiplicity of hinged sheets having the hinges arranged in stepped relation to accommodate the bulk of the photographs or samples mounted upon the sheets.

Other objects and advantages will hereinafter appear.

In the drawings forming part of the specification:

Fig. 1 is a plan view of an open album embodying features of the invention;

Fig. 2 is a sectional view taken on the line 2—2 of Fig. 1 looking in the direction of the arrows;

Fig. 2a is a view in elevation of a stud which is employed for anchoring and tensioning a hold down device;

Fig. 3 is a plan view of a modified form of folder or book;

Fig. 4 is a sectional view of the folder or book of Fig. 3, the attaching of the intermediate sheets being shown diagrammatically.

Fig. 5 is a sectional view illustrating a further modified form;

Fig. 6 is a sectional view of a folder or album generally similar to that of Figs. 1 and 2, but having the receptacle disposed outside the cover 10 hinges;

Fig. 7 is a sectional view showing a further embodiment of the invention;

Fig. 8 shows still another embodiment of the invention;

Fig. 9 is a fragmentary plan view of an open album similar to the album of Fig. 1 but including a modified construction of the means for providing spool or roll compartments;

Fig. 10 is a plan view of a further form of 20 album or carrying case, and

Fig. 11 is a fragmentary sectional view taken on the line 11—11 of Fig. 10 looking in the direction of the arrows.

In Figs. 1 and 2 the album 1 includes a cover 25 which comprises a front section 2, a back section 3, and an intermediate section 4 to which the front and back sections are hingedly connected. The hinging is effected in a well-known manner through flexible fabric. The intermediate section 4 forms a base for a receptacle 5, the receptacle as shown comprising side walls 6 and 7, end walls 8 and 9, and a hinged cover 10. The receptacle is provided, as seen in Fig. 1, with upright partitions 11 which extend nearly to the 35 top of the receptacle and may contain a series of small tubes 12, desirably of light metal or cardboard, for holding miniature film in spool form or in tubular containers. The tubes are removable and are open at both ends so that the 40 contained film can be pushed out of a tube conveniently and without any likelihood of its getting out of control and unwinding.

The front and back of the album and any intermediate sheets that may be provided are 45 provided with photograph hinges. These hinges may be of any suitable construction, but they are desirably formed from a sheet 13 of flexible fabric which is pasted to the cover or supporting sheet except in vertical hinge zones. In these 50 zones the sheet is gummed but it is not pasted down. Each hinge zone is divided into a multiplicity of hinges 14 by angular cuts 15. The hinges of the several zones are disposed in horizontally aligned sets so that a photograph may 55

be hingedly mounted in the album by attaching it to the aligned hinges of such a set. As shown in Fig. 1 each of the front and back sections of the album carries two columns or tiers of pictures.

5 When a sheet is filled it presents the appearance seen in Fig. 1. In this figure several of the photographs at the upper end of the second tier are shown turned up so as to expose the hinge structure to view, but when the folder or 10 album is to be closed these photographs would, of course, be turned downward like the photographs of the other tiers.

In order to protect the photographs and the 15 hinges when the front or back section or any intermediate photograph supporting sheet is turned, provision is made of an elastic band or tape 16 connected to anchor studs 17 at its ends. The elastic band is formed with loops or metal rings at its ends or it may be an endless elastic 20 band which can be stretched around the anchor studs and which contracts beneath the heads of the studs. The elastic can, therefore, be readily removed for replacement when it wears out. When the elastic is not in use it extends taut between the anchor studs as shown alongside the 25 second and fourth tiers of photographs in Fig. 1. When the elastic is to be put into use an intermediate portion is drawn around a stud 18 at the opposite side of the associated tier of photographs from the anchor studs 17 to which the elastic is connected. The arrangement shown in Fig. 1 with the stud 18 disposed adjacent the lower edge of the uppermost photograph is one which is very desirable in practice since this holds 30 the uppermost photograph or fabric sample against curling, and holds the lower margins of 35 all of the underlying photographs, fabric samples, etc., down against the sheet.

The anchor studs 17 and the studs 18 are of 40 similar construction. In the illustrative form each comprises a shank 19 which is passed through or partially through the cover or supporting sheet and properly fastened thereto. The stud may be passed through a washer 20 and 45 upset against the outer face of the washer to rivet the stud in place. Each stud desirably comprises a collar 21 which engages the supporting sheet and a head 22 spaced from the collar. The collar 21 and the head 22 define a circumferential groove 23 between them which receives and retains the elastic 16.

The embodiment of Figs. 3 and 4 is generally 50 similar to that of Figs. 1 and 2, but it includes a stepped hinge support alongside the central receptacle to which intermediate sheets are hinged. 55 This construction is a desirable one for use with photographs, but it is especially valuable for use with thicker bodies arranged in stepped relation, such as woolen samples. By hinging the intermediate sheets in stepped relation it is possible 60 to avoid having the accumulated bulk throw an excessive strain on the sheets adjacent the hinges or compel a divergence of the covers when the book or carrying case is closed, and it is also possible to assure that the sheets will be able to open 65 to a horizontal position.

In this form of the invention the book or carrying case 1a comprises a front cover section 2a and a back cover section 3a hingedly connected 70 to an intermediate cover section 4a. The intermediate section may carry a receptacle 5a as before but the intermediate section is considerably wider than the receptacle and it also has fixed upon it at each side of the receptacle 5a a stepped 75 support 25 to which intermediate sheets 26 are

hingedly connected, as shown in diagrammatic form in Fig. 4, the hinge line in each instance being at or adjacent to the vertex of a reentrant step angle. The front and back of the cover and each intermediate sheet is desirably constructed similarly to the front and back of the cover of Fig. 1, that is, hinges, hold down elastics, and studs for the anchoring and tensioning of the elastics, are provided on each sheet. A margin is left free on each sheet adjacent the hinge for a distance at least great enough to assure that nothing carried by the sheet will engage the associated step. It will be seen that the horizontal step webs or "treads", (by analogy to an ordinary flight of stairs) space the sheets when they are folded upward as seen in Fig. 4 so that the bulk of the carried material does not compel the sheets to gap apart when the book is closed. The vertical step webs, or "risers", (by analogy to an ordinary flight of stairs) similarly space the sheets at their inner margins when the book is open so that the sheets can all fold down to a horizontal position without throwing any great strain on the areas adjacent the hinges.

Since there is no assurance, however, that the 25 bulk of the material will build up a thickness equal to a step "riser" or "tread", it is desirable not to limit the turning of the sheets in Fig. 4 to horizontal and vertical positions but rather to permit them to cross both the horizontal and 30 vertical positions. In order to permit this freedom of movement the step "treads" are inclined downward slightly to the vertical, and the step "risers" are also inclined slightly to the vertical 35 to make the reentrant step angles slightly obtuse. Such steps and risers, however, may be perfectly horizontal and vertical, if desired. Another arrangement which would produce a similar result would be to run the sheet supporting members straight down at about the inclination at which 40 the steps of Fig. 4 run. The angle may, of course, be varied as desired.

In Fig. 5 disclosure is made of a book or carrying case 1b having a front cover section 2b, a back cover section 3b, and an intermediate cover 45 section 4b to which the front and back sections are hingedly connected. This form includes no receptacle upon the intermediate section 4b, but it does include a stepped formation 25b at either side of the section 4b, the stepped structures being 50 brought together in juxtaposed relation instead of separated to provide receptacle walls. The steps of Fig. 5 are shown as rectangular in form but they may also be inclined in the manner of 55 the steps of Fig. 4 if desired.

In Fig. 6 disclosure is made of a book or carrying case like the book of Figs. 1 and 2 except that the receptacle is located outside the cover hinges instead of between the foldable front and 60 back cover sections. In this form of the invention a receptacle 27 constitutes an intermediate cover section and has a front cover section 2c and a back cover section 3c hinged to it along its inner longitudinal edges. A cover 10c is hingedly 65 connected to the receptacle, and the interior construction of the receptacle may be the same as that of Fig. 1. The front and back cover sections 2c and 3c may be in all other respects exactly the same as the front and back cover sections 2 and 3 of Fig. 1.

This form of the invention has the advantage that intermediate sheets (which may be hingedly connected to the receptacle cover or to a flexible flap extending over the receptacle cover) can be 75

turned through 180 degrees so as to lie flat against either the front or back cover section.

In the embodiment of Fig. 7 disclosure is made of a book or carrying case 1d comprising a front cover section 2d and a back cover section 3d. The back cover section 3d includes a stiff wall 28 which extends at right angles to the remainder of the back cover section and forms a side wall of a receptacle 5d. The back cover section, itself, also constitutes the bottom of the receptacle as seen in Fig. 7. The receptacle is additionally provided with a side wall 29 and with end walls 30 of which only one is seen in the figure. A closure 31 is hinged to the wall 5d and extends across the top of the receptacle to the upper edge of the wall 28. The front cover section 2d is hinged to the upper edge of the wall 28, and when it is swung to close the book it extends over the top of the receptacle closure 31 and guards the receptacle closure against accidental opening.

In the form of the invention disclosed in Fig. 8 the album is generally similar to that of Fig. 1 with the exception that the receptacle is mounted along a margin of a cover section remote from the cover hinges and that the intermediate cover section is utilized throughout its width for hingedly mounting additional sheets between the covers.

In this form the album comprises a front cover section 2e, a back cover section 3e, and an intermediate cover section 4e to which the front and back cover sections 2e and 3e are hingedly connected. A receptacle 5e is mounted to extend along the margin of the front cover section 2e remote from the hinge of said cover section. The receptacle 5e is provided with a hinged closure 10e at its inner side, that is at the side which faces toward the album hinges.

Additional sheets 33 are hinged to the intermediate cover section 4e, the sheets being narrow enough to terminate short of the receptacle 5e. The back cover section 3e may be provided with a hinged latch or catch 34 which cooperates with a stud 35 on the receptacle 5e for securing the album in closed condition.

This embodiment has the advantages that the receptacle does not limit nor interfere with the provision of additional sheets between the cover. The album may be opened to lie flat on a table, and the intermediate sheets can be turned through 180 degrees without obstruction so that they may lie flat against either the front or back section of the cover.

The form of the invention disclosed in Fig. 9 is generally the same as that of Figs. 1 and 2. The same reference numerals have therefore been applied to corresponding parts with the subscript "f" added so that a detailed description is deemed unnecessary. The embodiment of Fig. 9 differs from that of Figs. 1 and 2, however, in that the hollow cylinders 12 of Fig. 1 are omitted and the compartment 5 is subdivided into minor compartments for containing rolls or spools of photographic film by means of partition strips 36 and cross spacers 37. Each of the strips 36 may be formed of thin sheet metal or other suitable material. The strips are alike in construction. Each strip is provided at uniform intervals with angular indentations or projections which extend toward the middle of the compartment 5. The angular projections of the two strips are paired so that they are disposed in opposing relation and hence serve to subdivide the compartment 5 into a series of smaller compartments, each adapted to hold a roll or spool of photographic film. Spacing partitions 37 which may also be of

sheet metal or other suitable material are inserted at intervals, each spacing partition being provided with a pair of slots to embrace opposing vertices of the partition strips.

In the form of the invention disclosed in Figs. 10 and 11 the cover comprises an intermediate section 4g and front and back sections 2g and 3g hingedly connected to the intermediate section. The back section has mounted upon it wide spacers 38 and narrow spacers 39 which together form a solid block. The spacers may be formed of cardboard or other suitable material. Leaf hinges for leaves 40 are provided by securing sheets of fabric 41 between adjacent spacers 38 and 39. The two fabric sheets at opposite sides of the spacer 39 are brought together outside the block and adhesively united for a short distance, their free ends being then adhesively united to opposite sides of the sheet 40. With this arrangement adequate provision is made for spacing the covers and the intermediate sheets apart and the sheet hinges are provided with a very secure anchorage through adhesive union with the adjacent spacers 38 and 39.

Reinforcement may be had by securing a fabric sheet 42 to the uppermost spacer 38 and to the front cover section 2g, and by securing a fabric sheet 43 to the lowermost spacer 38 and to the back cover section 3g.

While I have illustrated and described in detail certain preferred forms of my invention, it is to be understood that changes may be made therein and the invention embodied in other structures. I do not, therefore, desire to limit myself to the specific constructions illustrated, but intend to cover my invention broadly in whatever form its principle may be utilized as described and set forth in the appended claims.

I claim:

1. In an album, in combination, a front cover section, a back cover section, an intermediate cover section to which the front and back sections are hingedly connected, sheets hingedly mounted within the cover, and hinge supporting means carried by the intermediate section and providing a succession of hinge joints so arranged that the sheets progressing from the covers toward the middle of the album are hinged at progressively greater distances from the plane of the intermediate cover section, said hinge supporting means providing a series of steps, and the sheets being hingedly connected to it adjacent the vertices of the reentrant angles of the steps, the "risers" and "treads" of the steps being so inclined that the reentrant angles of the steps are obtuse.

2. In an album, in combination, a supporting sheet adapted to have a tier of photographs hingedly attached to it in stepped relation, a pair of anchor studs secured to the sheet alongside the photograph area, an elastic hold down band connected to the anchor studs, and an additional stud at the opposite side of the photograph area from the anchor studs, about which the elastic band may be passed to cause it to extend over the photograph area.

3. In an album, in combination, a supporting sheet adapted to have a tier of photographs hingedly attached to it in stepped relation, a pair of anchor studs secured to the sheet alongside the photograph area, an elastic hold down band connected to the anchor studs, and an additional stud at the opposite side of the photograph area from the anchor studs about which the elastic band may be passed to cause it to

extend over the photograph area, said additional stud having an enlargement or head at its upper end for retaining the elastic band against accidental separation from the stud.

5. In an album, in combination, a supporting sheet adapted to have a tier of photographs hingedly attached to it in stepped relation, a pair of anchor studs secured to the sheet alongside the photograph area, an elastic hold down band connected to the anchor studs, and an 10 additional stud at the opposite side of the photograph area from the anchor studs, about which the elastic band may be passed to cause it to extend over the photograph area, said additional stud having an enlargement or head at its upper 15 end for retaining the elastic band against accidental separation from the stud, and said anchor studs having enlargements or heads at their upper ends for retaining the elastic band against accidental separation from the anchor 20 studs.

5. In an album, in combination, a supporting sheet adapted to have a tier of photographs hingedly attached to it in stepped relation, a pair of anchor studs secured to the sheet alongside the photograph area, an elastic hold down band connected to the anchor studs, and an 25 additional stud at the opposite side of the photograph area from the anchor studs about which

the elastic band may be passed to cause it to extend over the photograph area, said additional stud having an enlargement or head at its upper end for retaining the elastic band against accidental separation from the stud, and said anchor studs having enlargements or heads at 5 their upper ends for retaining the elastic band against accidental separation from the anchor studs, and the elastic band having loops in its 10 ends adapted to be stretched over the heads of the anchor studs to permit ready attachment and removal of the band.

6. In an album, in combination, a supporting sheet, hinges mounted on the supporting sheet for supporting a tier of photographs in stepped 15 relation, hold down means carried by the sheet comprising two stop members having an elastic connection extending therebetween, and a third stop member mounted out of alignment with the first two stop members and adapted to be detachably engaged by the elastic connection, said elastic connection, when engaging the third stop member, overlying the tier of photographs and holding the tier of photographs in substantially flat relationship against the supporting sheet, 20 said elastic connection standing clear of the tier of photographs when not engaging the said third stop member.

ALBERT A. AINSWORTH.
